UNITED STATES PATENT OFFICE

PAUL EMIL FRANZ KRÜGER, OF COPENHAGEN, DENMARK

CONNECTER FOR CONNECTING MOVABLE ELECTRIC LINES

Application filed August 12, 1930, Serial No. 474,821, and in Denmark September 12, 1929.

The present invention relates to a connector adapted to be used in cases in which parts, to be connected together electrically, are adapted to be moved relatively with great facility. Such connectors may for example be used as intermediate members in electric conductors which must not be turned relatively as for example, in telephone lines, lines for dust suction devices, electric smoothing irons and electric tools, of the type including drilling machines and the like.

In an appliance of this character, which may be used both for continuous current and for alternating current, very considerable requirements are necessary as regards the electric contact as it is absolutely necessary to avoid creating a spark. It is also desirable for the connector to be capable of being moved easily so that the contact pressure on the supporting surface may not be too high. In addition it is also desirable for the appliance to be of very small dimensions whilst not going below the lowest permissible cross sections or beyond the lowest permissible intervals between the separate parts which are under different voltages. Finally the appliance must be of such strong construction that it cannot be destroyed by pressure or tension stresses, which however do not include the application of force.

These various requirements which would appear contradictory are accomplished by means of the present construction which produces an easy connection, is capable of withstanding a larger electrical load than that for which it is constructed, and which is capable of withstanding heavy mechanical movement and forcible movements of the two contact parts relatively to one another, all of which may take place without creating sparks or current interruptions, it being within its province to even be included in a radio apparatus without producing audible disturbances when the appliance is being moved.

This result is obtained by means of my invention which comprises a connector having two contact parts of which one is formed of relatively insulated discs rigidly secured

to a supporting member, each disc being electrically connected to one of the lines to be connected together and to the other contact part of conducting spring brushes, the other contact part being formed of conducting housings, one housing for each disc, which housings surround the discs with a certain amount of free space partly filled by the brushes.

The invention is illustrated in the accompanying drawing wherein

Fig. 1 is a substantially longitudinal sectional view of the connector taken on lines 1—1 of Figure 3; Fig. 2 is a similar view showing certain parts on a larger scale; and Fig. 3 is a substantially transverse sectional view taken on lines 3—3 of Figure 1.

The connector consists, in the form of construction illustratively exemplified in the drawing, of an insulated pipe 1, to which are secured a number of electric current conducting discs 2. The discs 2 are connected by lines 3 following through the pipe 1 to terminal screws 4 which are mounted on an insulated disc 5 secured to one end of the pipe 1. The other end of the pipe is provided with an axially disposed bearing pin 7 which is rotatably mounted in a center opening in an insulated disc 6. Adjacent the disc 5 the pipe 1 is rotatably mounted in a second disc 8 having a center opening 9 through which the pipe 1 projects. The two discs 6 and 8 are connected together by longitudinally disposed actuately spaced connecting rods 10 corresponding in number to the number of discs 2 on the pipe 1.

The rods 10 carry insulating rings 11 which are arranged side by side in pairs and the rings of each pair are clamped together on the rods 10 by nuts 12. Between each pair of rings are clamped two shells which together form housings 13 loosely embracing the discs 2 so that a space is formed between the discs 2 and the housings 13. The housings 13, as shown in Fig. 3, are circular members and each has a projection 14 with a hole accommodating one of the rods 10 so that a conducting connection is formed between this rod 10 and the housing. Adjacent the other rods 10 each housing is pro-

vided with recesses 15 so that it does not come in contact with these rods and is so spaced from them that arcing between a rod 10 and the housing 13 is not liable to occur.

5 The housings 13 are provided with central openings, the walls of which do not approach the wall of the pipe 1 so that a space 16 is left to permit the housings to rotate freely about the pipe.

10 Contact brushes 17 are disposed in the housings 13 between the latter and the discs 2 whereby contact is formed, the brushes 17, comprising bundles of very fine metal wires secured to the outer side of the housings and 15 passing through recesses 18, cut in the rim thereof into the interior of the housings where contact is made with the discs 2.

In accordance with this brush construction it is easily possible to obtain sufficient cross 20 sectional area for the transmission of any current load which it may be called upon to carry, the contact being made with a minimum of contact pressure. In addition a 25 large number of contact brushes (in the drawing 6 are shown) can be used to effect a contact between each housing and the corresponding disc so that there will be no possibility of a failure to maintain the contact.

As will be seen in Fig. 2 the brushes 17 surround the discs 2 on both sides thereof so 30 that the discs are not moved laterally, and contact between the housings 13 and discs 2 is not interrupted. The separate brush wires are each constructed to form a comparatively 35 large loop which is readily pliable at its inner end bearing against the disc.

The connector operates in the following manner, the one part of the lines 19 or 20 are connected to the rods 10 by means of 40 terminal screws 21 which are secured thereto, whilst the other part of the lines 22 and 23 is connected to the terminal screws 4. The electric current is then for example conducted from the line 19 through the corresponding 45 rod 10 to one of the housings 13 and from there it is conducted by the corresponding brushes 17 to the corresponding disc 2 and from there through one of the lines 3 to one line 22 or 23.

50 It will be seen that the connector part formed of the pipe 1 and the discs 2 is very easily rotatable relatively to the part formed of the housings. A relative axial movement of these two parts can be effected easily without interrupting electrical contact. The contact also has great resistance to mechanical strains.

The connector may be enclosed in a casing 24 so as to prevent it from being touched.

60 The connector may be used wherever it is desired to avoid binding together electric lines either by using the connector as an intermediate member included in the line or by forming one part, pole (21), as a plug whilst 65 the other part is formed as a socket so that

the socket branches of the line can be plugged in directly. The connector may be provided with any desired number of discs and housings and may be mounted in electrical apparatus or the like for example in lamp 70 holders, dust suction devices and the like or in electrical machines either as a part of the machines themselves or as a part of their supply lines as for example in electric drilling machines or the like.

75 What I claim as new is:

An electrical connector for movable electric lines comprising in combination a plurality of relatively insulated conducting discs, a common support for said discs, each of said discs being connected to the end of one of said lines, and a plurality of relatively insulated conducting housings, one thereof embracing each disc, a common support for said housings, said supports being rotatable 80 in relation to each other, each of said housings embracing loosely both sides of one disc and thin metallic brushes carried by the 85 housings in the spaces between the latter and the discs and in contact with the discs, each 90 of said housings being connected to the other end of one of said lines.

95 In testimony whereof I affix my signature.

PAUL EMIL FRANZ KRÜGER.
